**COMBINATION FLUSH AND EDGE PULL FOR
SLIDING DOORS**

Walter J. Duvall, Chula Vista, Calif.

Application November 5, 1954, Serial No. 32,966

Term of patent 7 years

(Cl. D10—8)

FIG. 1

FIG. 2

Fig. 1 is a side elevational view of a combination flush and edge pull for sliding doors embodying my new design, the opposite side being substantially identical therewith; and

Fig. 2 is a front elevational view of the same.

I claim:

The ornamental design for a combination flush and edge pull for sliding doors, substantially as shown and described.
